US00D869793S

(12) **United States Design Patent** (10) **Patent No.:** **US D869,793 S**
(45) **Date of Patent:** ** *Dec. 10, 2019

(54) **FLOOR CLEANING DEVICE**

(71) Applicant: **Carl Freudenberg KG**, Weinheim (DE)

(72) Inventor: **Luca Casini**, Milan (IT)

(73) Assignee: **CARL FREUDENBERG KG**, Weinheim (DE)

(*) Notice: This patent is subject to a terminal disclaimer.

(**) Term: **15 Years**

(21) Appl. No.: **29/595,181**

(22) Filed: **Feb. 27, 2017**

(30) **Foreign Application Priority Data**

Aug. 30, 2016 (EM) 003357292

(51) **LOC (12) Cl.** **15-05**

(52) **U.S. Cl.**

USPC **D32/15**; D32/51

(58) **Field of Classification Search**

USPC D32/15, 20, 22, 34, 31, 50, 25, 51, 38;

D4/137

CPC A47L 9/2857; A47L 9/02; A47L 13/146;

A47L 13/12; A47L 13/20

(57) **CLAIM**

The ornamental design for a floor cleaning device, as shown.

DESCRIPTION

The patent or application file contains at least one drawing executed in color. Copies of this patent or patent application publication with color drawing(s) will be provided by the Office upon request and payment of the necessary fee.

FIG. 1 is a top right front perspective view of the floor cleaning device showing my new design;

FIG. 2 is a bottom plan view thereof;

FIG. 3 is a rear elevational view thereof;

FIG. 4 is a front elevational view thereof;

FIG. 5 is a left side elevational view thereof;

FIG. 6 is a right side elevational view thereof; and,

FIG. 7 is a top plan view thereof.

1 Claim, 7 Drawing Sheets
